UNITED STATES PATENT OFFICE.

FRED H. DANIELS, OF WORCESTER, MASSACHUSETTS.

CHARGING APPARATUS.

956,890.

Specification of Letters Patent. Patented May 3, 1910.

Application filed August 21, 1909. Serial No. 514,009.

To all whom it may concern:

Be it known that I, FRED H. DANIELS, of Worcester, Worcester county, Massachusetts, have invented a new and useful Improvement 5 in Charging Apparatus, of which the following is a full, clear, and exact description, reference being had to the accompanying drawings, forming part of this specification, in which—

10 Figure 1 is a plan view of a billet-charging apparatus embodying my invention; Fig. 2 is a longitudinal section of the same; Fig. 3 is an end elevation.

15 My invention has relation to apparatus for charging heating furnaces and is designed to provide apparatus of this character which will always be in condition to operate regardless of weather conditions and which is so arranged as to provide for the 20 storage of billets or other blanks at the extreme end of the apparatus, which may be outside of the building in the storage yard of the plant, thus saving room in the building itself.

25 Other objects and advantages of the invention will hereinafter appear.

In the embodiment of my invention shown in the drawings, I have indicated a double width furnace 2, together with two independent chargers arranged side by side, for 30 charging two rows of blanks into the furnace. But one of these charging apparatus will be described in detail, corresponding reference characters being applied to the 35 other apparatus.

3 designates the bed of the apparatus upon which is supported the slideway 4, for the series of billets 5, to be pushed into the furnace chamber. These billets are delivered 40 upon the slideway 4 from any suitable conveyer, preferably a car 6, running on the tracks 7, arranged transversely at the outer end of the apparatus.

8 designates the pusher bar having hinged 45 to its outer end an arm 9, which, upon the forward stroke of the bar 8, is arranged to engage the billets on the car, as indicated in Fig. 2, and push the same on to the slideway 4, the arm being held rigid during this 50 movement of the bar by its engagement with the shoulder 10 thereon. During the reverse movement of the bar, the arm swings out of the way and slides over the billets until the end of the row is reached. The bar is actuated by means of a rack 11, secured thereto 55 and engaged by a pinion 12, on a shaft 13,

driven through the chain of gears 14, forming the slow-down gearing, by an electric motor 15. The bar 8 is suspended at one end by the wheels or rollers 16, which travel on the beams or girders 17. These beams or girders are supported at their rear ends from the bed or foundation of the apparatus, as indicated at 18, and at their opposite ends are supported from the furnace 2, as indicated at 19. The pinion 12 also forms a support for the bar, and a roller 20 journaled on the fixed frame member 21 and bearing on the upper surface of the bar, serves to take the upward thrust from the 70 gears.

The operation will be readily understood. When the motor 15 is operated, the arm 8 is reciprocated and each forward stroke pushes a series of billets from the car 6 on 75 to the slideway 4, at the same time moving the entire series of billets continuously along the slideway and through the furnace which is of the continuous type. During the reverse movement of the pusher bar, the arm 80 9 slides freely over the supports in the manner before described.

The shafts of the two motors may be connected, if desired, as shown in Fig. 1. The advantage of connecting the shafts of the 85 two motors in this manner is that the two pushers may be made to act as one, in case long billets are charged into the furnace, that is to say, the two racks will travel together in the same direction, and at the same 90 time, and the billet which extends clear across the furnace, or which is twice the length of the billets ordinarily used, can be charged through the furnace.

The advantages of my invention will be 95 apparent to those skilled in the art. The customary way heretofore of charging a billet-heating furnace has been by means of a hydraulically-operated pusher, which forces a number of billets into the furnace from a car placed between it and the pusher or from a stationary support on which layers of billets are successively placed, by means of a suitable overhead crane. The serious disadvantage of this arrangement is that in 105 cold weather, the pusher is liable to be rendered inoperative, due to freezing of the water. As the furnaces should be placed inside the building, but as near the outside 110 billet yard as possible, the use of a hydraulic pusher of this common type necessitates either running the track for the cars into.

the building or providing room for the row of billets in front of the pusher. In both cases, much room is required in the building. In the arrangement shown, the apparatus is 5 always ready to operate, regardless of weather conditions and the storage of billets is at the extreme end, which may be outside in the billet yard, thus saving room in the building itself.

- 10 It will be obvious that various changes may be made in the details of construction and arrangement of the several parts, without departing from the spirit and scope of my invention, as defined in the appended 15 claims. Thus, the manner of supporting the pusher bar may be changed, any suitable arrangement of actuating gearing between the motor and the pusher bar may be employed, and various other changes may be made. 20 The pusher bar and arm or finger may also be actuated by other means, such as a hydraulic or pneumatic cylinder placed over the billet slideway, and inside the building.

Instead of employing the apparatus with 25 a double width furnace, two single width furnaces may be used when preferred but one charging mechanism being employed with each furnace in such case, and the charging mechanisms may be connected so 30 as to move in unison or not as is desired.

I claim:

1. Furnace charging apparatus comprising a reciprocating pusher bar having means arranged to contact with and push blanks 35 supported beneath said bar into the furnace, a track for said pusher bar, a rotary driving motor and gearing operatively connecting said motor and pusher bar; substantially as described.
- 40 2. Apparatus for charging furnaces comprising a slide-way on which blanks are transferred to the furnace, a reciprocating pusher arranged to travel above the slide-way and having a pivoted pusher arm contacting with said blanks, a rotary driving motor and gearing operatively connecting said motor with the pusher; substantially as described.

3. Apparatus for charging furnaces comprising a supporting slide-way for the blanks, a pusher bar arranged to reciprocate over and above the slide-way, said bar having a toothed rack attached thereto, guides for the bar, a rotary driving motor and 55 gearing operatively connecting said motor

with the rack on said bar; substantially as described.

4. Apparatus for charging furnaces comprising a slide-way on which blanks are supported, a track adjacent thereto, a pusher bar arranged to reciprocate over the slide-way and track having a pivoted pusher finger adapted to contact with the blanks, a rotary driving motor and gearing operatively connecting the motor with said pusher bar; substantially as described.

5. Apparatus for charging furnaces comprising a slide-way on which the blanks are supported and moved into the furnace, a track above the slide-way, a reciprocating pusher bar mounted upon and adapted to travel on said track, said pusher bar having a toothed rack secured thereto, a rotary driving motor and means operatively connecting the motor with the rack on said pusher bar; substantially as described.

6. Apparatus for charging furnaces comprising a support for the blanks to be charged into the furnace, a reciprocating pusher bar, a pusher finger connected to the bar arranged to contact with the blanks and means for reciprocating the pusher bar and finger above said slide-way; substantially as described.

7. Apparatus for charging furnaces comprising a slide-way on which blanks are movably supported, a reciprocating pusher bar above said support, a pusher finger pivoted to said bar, said finger being free to swing in one direction and means for reciprocating said bar above the supporting slide-way and moving materials supported on the slide-way forwardly toward the furnace; substantially as described.

8. Apparatus for charging furnaces comprising a supporting slide-way for the blanks, a plurality of reciprocating pusher bars mounted above the supporting slide-way, separate driving motors for actuating the pusher bars and means connecting said motors adapted to cause the pusher bars to reciprocate in unison; substantially as described.

In testimony whereof, I have hereunto set my hand.

FRED H. DANIELS.
